CLAIM

The ornamental design for a combined chair and television viewer, as shown and described.

DESCRIPTION

FIG. 1 is a front perspective view of a combined chair and television viewer showing my design.

FIG. 2 is a view in front elevation showing the combined chair and television viewer on a reduced scale;

FIG. 3 is a top plan view of the design;

FIG. 4 is a view of the design in elevation from one side;

FIG. 5 is a view of the design in elevation from the opposite side;

FIG. 6 is a view of the design in elevation from the rear;

and

FIG. 7 is a bottom plan view thereof.
